His Attorney.

UNITED STATES PATENT OFFICE.

STEWART L. CLOTHIER, OF SCHENECTADY, NEW YORK; FRANK S. CLOTHIER, GUARDIAN OF SAID STEWART L. CLOTHIER, ASSIGNOR TO GENERAL ELECTRIC COMPANY, A CORPORATION OF NEW YORK.

ELECTRON-DISCHARGE APPARATUS.

Application filed May 29, 1924. Serial No. 716,821.

My present invention relates to electron discharge apparatus, and more particularly to circuit connections for devices of the thermionic type having at least four electrodes.

One of the objects of my invention is to provide an improved circuit organization for use with a device of the type mentioned whereby the amplification which may be obtained with such a device may be increased.

In connection with electron discharge devices of the thermionic type having a grid for controlling the flow of current between cathode and anode it has been proposed to employ a second grid between the cathode and control grid, and to impress upon this second grid a constant positive potential somewhat lower than that of the anode.

A grid used in this way is commonly known as a space charge grid. The purpose of this grid is to lower the impedance between the cathode and anode, and for this purpose the grid has ordinarily been maintained at a constant positive potential. It has been observed, however, that the current flowing from this space charge grid varies in the opposite way from the manner in which the current to the anode varies when acted upon by the control grid. That is, as the current to the anode increases the current to the space charge grid decreases, and vice versa.

If an impedance is placed in circuit with the space charge grid the current variations in the circuit of the space charge grid will cause the potential of the space charge grid to vary.

A more specific object of my invention is to produce potential variations of the space charge grid which will act upon the control grid through the capacity existing between the two grids, and produce what is commonly known as a regenerative effect, thereby increasing the amount of amplification which can be produced by means of the tube.

It has been proposed in Van der Bijl Patent 1,479,779 to provide an inductive feed-back coupling between the circuit of the space charge grid and the circuit of the control grid and produce regeneration in this way. In this case the direction of the coupling between the two circuits must be

arranged in the opposite manner to that of the usual regenerative coupling between the plate and grid circuits of a three-electrode device because of the fact that the currents in the space charge grid circuit vary in the opposite manner to those in the plate circuit.

I have discovered that a regenerative effect may be produced with a four-electrode tube without the use of an inductive feed-back coupling. While it is also known that a regenerative effect can be obtained in a three-electrode device, by reason of the capacity coupling between the plate and grid, when the plate circuit is properly tuned, the usual adjustment of the plate circuit employed in this case is not suitable for the adjustment of the circuit of the space charge grid in the four-electrode device because of the fact, as pointed out above, that the current in the two circuits vary in opposite directions. I have discovered that the desired feed-back through the capacity between the two grids may be obtained if the impedance of the space charge grid has a suitable capacity reactance.

The novel features which I believe to be characteristic of my invention are set forth with particularity in the appended claims, my invention itself, however, both as to its organization and method of operation will best be understood by reference to the following description taken in connection with the accompanying drawing in which Figs. 1 and 2 show diagrammatically two different circuit arrangements which may be employed for carrying my invention into effect.

I have indicated in the drawing the application of my invention to the reception and detection of radio signals. I have shown in the drawing an electron discharge device 1 having the usual electron emitting cathode 2, anode 3, control grid 4, and space charge grid 5. Signals from the antenna 6 are impressed upon the circuit of the control grid in the usual manner. The space charge grid 5 is connected by a suitable tap 7 to the battery 8, which supplies the necessary plate potential for the operation of the device.

In Fig. 1 I have shown in the circuit of the space charge grid a variable inductance

9 and variable capacity 10 in parallel. By suitable adjustment of these impedances the desired regenerative effect may be obtained. I have found that the adjustment of the circuit is not especially critical as when it has once been adjusted to a sensitive point it is still sensitive over a considerable range of wave lengths. It does not require readjustment every time that the tuning of the in-
10 put circuit is changed.

The arrangement of Fig. 2 differs from that of Fig. 1 only in that the entire adjustment of the circuit of the space charge grid is accomplished by means of a variometer 11. I have found that the natural capacity of the variometer, which I have indicated by a shunt condenser 12, is in some cases sufficient to produce the proper adjustment of the phase relation of the potential of the space charge grid with respect to that of the control grid to produce the desired regeneration.
15

While I have shown and described only two modifications of my invention, it is evident that the phase of the potential of the space charge grid with respect to that of the control grid may be adjusted in various other ways to secure the desired result and that my invention may be employed with any type of circuit connection in which regenerative amplification is desired.
20

What I claim as new and desire to secure by Letters Patent of the United States, 25 is:—

1. An amplifying apparatus comprising an electron discharge device having an electron emitting cathode, an anode and two grids interposed between cathode and anode, 30 circuit connections between the cathode and each of the other electrodes, means for supplying electrical variations to be amplified to the circuit between the cathode and the grid nearest the anode, means for producing 35 resultant variations of the potential of the grid nearest the cathode, and means for adjusting the phase of the resultant variations

in the potential of the grid nearest the cathode to produce an increased amplification.
50

2. An amplifying apparatus comprising an electron discharge device having an electron emitting cathode, an anode and two grids interposed between cathode and anode, circuit connections between the cathode and each of the other electrodes, means for supplying electrical variations to be amplified to the circuit between the cathode and the grid nearest the anode, means for producing resultant variations of the potential of the grid nearest the cathode, and means for adjusting the phase of the resultant variations in the potential of the grid nearest the cathode to produce an increased amplification by reason of the capacity relations between the two grids.
55

3. An amplifying apparatus comprising an electron discharge device having an electron emitting cathode, an anode, and two grids interposed between cathode and anode, circuit connections between the cathode and each of the other electrodes, means for supplying electrical variations to be amplified to the circuit between the cathode and the grid nearest the anode, and means for producing a regenerative effect by reason of the capacity relations between the two grids, and thereby increasing the amplification.
70

4. An amplifying apparatus comprising an electron discharge device having an electron emitting cathode, an anode and two grids interposed between cathode and anode, circuit connections between the cathode and each of the other electrodes, means for supplying electrical variations to be amplified to the circuit between the cathode and the grid nearest the anode, and means for impressing upon the grid nearest the anode through the capacity between the two grids electrical variations substantially in phase with those originally supplied thereto.
75
80

In witness whereof, I have hereunto set my hand this 28th day of May 1924.
